FIG. I

FIG. 2

FIG. 3

FIG. 1 is a perspective view of a sign showing our new design;

FIG. 2 is an elevational view taken from one side thereof, the opposite side being the same as the side shown; and

FIG. 3 is an elevational view taken from one end thereof.

The dominant features of our design reside in the portions shown in full lines.

We claim:

The ornamental design for a sign, substantially as shown and described.
